UNITED STATES PATENT OFFICE.

JOHAN S. FASTING, OF VALBY, NEAR COPENHAGEN, DENMARK, ASSIGNOR TO F. L. SMITH & CO., OF NEW YORK, N. Y., A CORPORATION OF NEW JERSEY.

ROTARY KILN.

Application filed September 8, 1923. Serial No. 661,620.

To all whom it may concern:

Be it known that I, JOHAN S. FASTING, a subject of the King of Denmark, residing in Monrads Alle 9, Valby, near Copenhagen, Denmark, have invented certain new and useful Improvements in Rotary Kilns, of which the following is a specification, reference being had to the accompanying drawing, forming a part hereof.

10   Rotary kilns, such as those which are used in the sintering of cement raw materials and are of great length, as heretofore constructed have usually been made of cylindrical or tubular sections of sheet metal, of 15 uniform diameter, butt-joined to form a continuous tube by butt-straps of sheet metal which cover the butt-joints between the sections and are riveted to adjoining sections. The kiln thus produced, being of 20 uniform diameter from end to end, is not of such shape as to yield the best results in the burning of the cement raw materials. The velocity at which the materials being burned travel through a cylinder of uniform 25 diameter from end to end will obviously be substantially the same at every part of the cylinder, the inclination at the bottom part of the cylinder, on which the materials are supported, being the same at all points. Under 30 ideal conditions of operation, however, the materials under treatment should move at a greater velocity through certain zones of the kiln than through others. Thus, particularly in cement burning kilns, the 35 materials should pass through the drying zone, that is, the upper zone or the zone nearest the end at which the materials are fed into the kiln, more rapidly than through the burning zone, nearer the discharge end 40 of the kiln, in which the sintering of the materials is carried on. It is also desirable, in the operation of such kilns, that the velocity of the hot products of combustion should increase toward the end of the kiln 45 at which they escape and at which the raw materials are fed in. It has been proposed heretofore to meet the requirement for the relative reduction of the speed of travel of the materials being treated through the 50 burning zone by making the corresponding portion of the kiln of relatively larger diameter, but the construction proposed has been such as to introduce practical difficulties in construction as well as in operation. 55   By the construction which forms the sub-

ject of the present invention it is possible both to meet the technical requirements with regard to the speed of travel of the material and of the hot products of combustion through different portions of the kiln and 60 also to reduce the cost of construction as compared with that of the ordinary construction and also of the modified construction referred to. In accordance with the invention the improved kiln is made up of 65 cylindrical or tubular sections as before, but each successive section is smaller than the next adjacent section on one side by the thickness of the sheet or plate of metal employed so that it fits into the end of such 70 next adjacent section and is secured thereto by riveting or other suitable means. The invention will be more fully explained hereinafter with reference to the accompanying drawing in which it is illustrated and in 75 which—

Figure 1 is a view in elevation of a kiln constructed in accordance with the invention, with some of the appurtenant devices, and

Figure 2 is a partial view of the same in longitudinal section and on a larger scale.

That portion of the kiln, usually at about the middle, which should have the greatest diameter and in which the materials being burned should have or commence their slowest travel, is formed of a cylindrical or tubular section a of maximum diameter. The next adjacent section a' , at one side or at each side as the case may be, is of a 85 diameter less than that of the section a by substantially the thickness of the metal employed so that it can be fitted into the end of the section a for a distance sufficient to make a tight joint and to permit it to be secured therein by any suitable means, such as rivets, indicated at a'' . In like manner each successive section, as a' , a'' , a''' , etc., is smaller in diameter than the one next it and is lapped within it and secured 90 as before. The construction is continued in this way until a kiln of the required length is constructed or for such distance as it is desired to continue the reduction in diameter. At suitable points the kiln may be 95 provided, as usual, with bearing rings b which rest upon rollers c , the latter being mounted on suitable foundations d which are so proportioned as to give the kiln the desired inclination.

- As will be observed by reference to the drawings, the inclination of the bottom of the kiln, on which the materials are supported during their progress through the kiln, is greatest in the upper or feeding portion of the kiln in which the materials are subjected to the drying action, while the inclination of the bottom portion of the kiln toward the lower or discharge end is least.
- 5 Thus the materials being treated will travel with a maximum velocity through the drying zone and with a minimum velocity through the lower or burning zone. Furthermore, it will be observed that the saving of weight of metal employed in the new construction is considerable, not only by reason of the successively smaller diameters of the sections employed, but also by reason of the fact that the overlap of 10 two adjacent sections may be only about half of the width of the butt-strap hereto-
- 15
- 20

fore employed. Furthermore, the labor employed in the construction of the new kiln is less than in the construction of the old form of kiln because the overlap of two adjacent sections can be secured by a single line of rivets whereas two lines of rivets are required for each butt-strap heretofore employed.

25 I claim as my invention:

30 A rotary kiln formed of a series of tubular sections of successively reduced diameters with the section of maximum diameter between the ends of the kiln and the successive sections toward each end of the kiln 35 of successively reduced diameters and secured within the next adjacent section at one side.

This specification signed this 11th day of August, A. D. 1923.

JOHAN S. FASTING.
